UNITED STATES PATENT OFFICE.

HENRY B. FORD, OF ELYRIA, OHIO.

CARBURETER.

1,177,940.

Specification of Letters Patent.

Patented Apr. 4, 1916.

Application filed October 24, 1908, Serial No. 459,433. Renewed February 29, 1916. Serial No. 81,291.

To all whom it may concern:

Be it known that I, HENRY B. FORD, a subject of the King of Great Britain, residing at Elyria, in the county of Lorain 5 and State of Ohio, have invented a certain new and useful Improvement in Carbureters, of which the following is a specification.

The invention relates to the production of an explosive mixture of air and hydrocarbon vapor for use in internal combustion engines, and consists in a carbureter wherein oil or mixtures of oil, or other heavy hydrocarbons may be vaporized and commingled with air.

15 The process consists broadly in leading to a mixing chamber a predetermined amount of liquid hydrocarbon preheated to a point where its vapor tension is substantially equal to that of gasoline vapor at 60 degrees viz the tension at which gasoline 20 normally admitted to the carbureter (or explosion chamber, in the absence of a carbureter) in gasoline engines, and there mixing said hydrocarbon in the form of a 25 heated liquid spray, with air, whereupon said hydrocarbon is vaporized and with the air forms an explosive mixture adapted to be utilized in an explosion engine in precisely the same way that an explosive mixture 30 comprising gasoline is customarily employed.

The apparatus embodies the combination in a carbureter having a mixing chamber provided with an air inlet, of means for 35 heating a liquid hydrocarbon heavier than gasoline, and means for regulating the admission of said heated liquid hydrocarbon into said mixing chamber; also the various combinations more particularly pointed out 40 in the claims.

In the accompanying drawings—Figure 1 is a side elevation of my carbureter, showing the heating vessel in vertical section. Fig. 2 is a horizontal section on the line 2, 2, 45 of Figs. 1 and 4. Fig. 3 is a top view. Fig. 4 is a vertical section on the line 4, 4, of Fig. 3. Fig. 5 is a section on the line 5, 5, of Fig. 4. Fig. 6 is a section on the line 6, 6, of Fig. 4. Fig. 7 is a section on the 50 line 7, 7, of Fig. 3, and Fig. 8 is a section on the line 8, 8, of Fig. 3. The sections are viewed in the direction of the arrows.

Similar numbers and letters of reference indicate like parts.

55 The shell of the device is formed preferably in two parts, A and B. The part A

has a cylindrical chamber 9, provided with a threaded inlet connection 10, and a threaded outlet connection 11. To one of these connections is to be attached a pipe leading 60 from the exhaust of the internal combustion engine, which receives its gas from the carbureter. To the other connection is to be attached the pipe leading to atmosphere, or to the usual exhaust muffler.

65 The lower portion of the part B passes through an opening in the bottom of chamber 9 and is exteriorly threaded to receive a nut 12, by means of which the upper shouldered portion of said part is brought 70 tightly down upon the upper rim of part A, so that in this way the two parts of the shell are detachably secured together.

In the lower portion of part B is a vertical cylindrical chamber C, closed at the 75 bottom by a flanged screw plug 13. In this chamber is a cylindrical float D from which depends a guide rod 14 entering a vertical tubular opening in plug 13. Extending upwardly from float D is a rod E which is 80 shouldered, so that it forms a valve which is seated in the lower end of a vertical passage, which communicates with a horizontal passage 15 receiving a pipe G which is to lead to a source of kerosene or other suitable 85 oil, the supply of which oil is controlled by a faucet valve at g. The function of the float D is to regulate the quantity of oil entering chamber C, so as to keep said oil at a constant level. This it does by closing the 90 valve E when it is sufficiently raised by the oil accumulated in said chamber. In order to prevent the valve E from sticking, I provide a rod d, which extends up through a fixed sleeve e, and after passing through the 95 top of part B, is headed and provided with a helical spring f, which normally keeps said rod in raised position, or retracts thereto after said rod has been pushed down to depress said float, and so open valve E.

100 It will also be noted (Fig. 8) that sleeve e is open at the top to atmosphere so that the chamber C is maintained at atmospheric pressure even though the oil therein should become heated to such an extent as to tend to raise the pressure in the chamber—the effect of which would be to prevent the flow of oil through the passage 15 to said chamber.

105 On the side of chamber C is formed an offset 16, in which is secured one end of a coiled pipe F, which is wound around the

110

exterior of part B within chamber 9, and terminates in a side opening formed in a projection 17 on the opposite side, of said part, from that on which offset 16 is located. 5 As here shown, coil F makes one and a half turns. The length of the coil F must be varied to suit the particular oil employed and must be determined by experiment. Thus obviously for crude oil or a heavy tar 10 oil it must necessarily be longer than for kerosene. In any case the length must be such as to raise temperature of the oil used to a point where its vapor tension corresponds substantially to that of gasoline at 15 about 60 degrees. If raised higher than this the oil becomes coked and the deposit in the coil rapidly chokes the latter and renders the apparatus useless. In the projection 17 and adjacent solid portion of part B, is a 20 horizontal passage 18, with which coil F communicates. At its outer end said passage is closed by a removable screw 19. At its inner end it is intersected by an enlarged threaded opening which receives the valve 25 seat 20: said valve seat has a vertical passage flared at its upper end, and there receives the needle valve K, the stem 21 of which is threaded at its upper end to pass through a bushing 22 in the top of part B, 30 so that by turning stem 21, the needle valve K can be opened or closed to the desired extent.

On each side of the portion of part B, in which the valve seat 20 is located, is a vertical passage H, Fig. 2. These passages open 35 into the atmosphere at their lower ends 24, Fig. 4, and at their upper ends into the mixing chamber I in part B, and through them enters into said chamber atmospheric air 40 which is to be mixed with the hydrocarbon, to form the explosive mixture to be used in the engine. In coming through said passages, said air becomes somewhat, but not materially heated before entering the mixing 45 chamber.

While it is advantageous to somewhat warm the air admitted to the mixing chamber, it is a disadvantage to heat it to a high temperature since in its consequently expanded condition, a considerably less quantity may enter the chamber and a corresponding decrease in the amount of oxygen results—thereby lessening by so much the combustibility of the charge. A large supply of oxygen is necessary—and for this reason the air passages H are short and the air is not heated to a high temperature. Furthermore being in proximity to the oil chamber C the inflowing air tends to prevent the 55 temperature of the oil in this chamber from becoming so high as to coke and thus choke the outlet to pipe F.

Formed in part B, and parallel to the oil passage 15, is another passage 25 which 60 communicates at its outer end with a pipe

J, leading from a source of gasoline or other light hydrocarbon, said pipe having a controlling faucet valve j. The passage 25 communicates at its inner end with a vertical passage 26, Fig. 7, which opens into mixing 70 chamber I. The upper end of passage 26 is closed by a needle valve N, the threaded stem 27 of which passes up through the top of part B. When the faucet valve j and the needle valve N are opened, gasoline can enter 75 the mixing chamber I and flow over the upper surface of the partition in which the passages 15 and 25 are formed.

In the top of part B is an opening threaded to receive a spider 28, centrally disposed 80 in which is a sleeve 29 which receives a disk valve L, closing said opening and bearing against the under side of said spider. Said valve is held to its seat by the stem 30 carrying a disk 31, between which disk and valve 35 L is interposed the helical spring 32. The upper end of stem 30 extending above sleeve 29 is threaded to receive a nut 33, by means of which the spring pressure on the valve L may be regulated. The function of valve L 90 is to admit an additional supply of atmospheric air to the mixing chamber, under conditions hereinafter set forth.

On one side of the mixing chamber I is the outlet duct 34, provided with the pivoted valve M, operated by handle 35.

The operation of the entire apparatus is as follows: Faucet valve g, in the oil pipe G, is opened to admit oil into chamber C. This oil fills the coil F and rises in chamber C 100 until it reaches a predetermined level, when the float D closes valve E and so prevents the entrance of a further supply. Faucet valve j, in the gasoline pipe J, is also opened, and the needle valve N is raised to permit a 105 small amount of gasoline to flow, as described, into the mixing chamber I. The engine is now cranked, or otherwise started by hand, the valve M being adjusted permanently to a desired opening. The suction of the engine then draws from the mixing chamber I the vapor of the gasoline, just admitted, mixed with air entering through the passages H. This mixture, being ignited in the engine cylinder in the 115 usual way, starts the engine into automatic operation and establishes the flow of hot exhaust gas through the chamber 9. This heats the oil in the coil F and float chamber C. When a temperature is reached at 120 which the oil has acquired a vapor tension substantially equal to that of gasoline at 60 degrees, or in other words has reached a temperature at which it flashes, say 150° for ordinary kerosene, the gasoline supply 125 is shut off completely. The hot oil, sucked in by the engine, escapes in the form of spray past the needle valve K, which has already been adjusted to a predetermined opening, meeting meanwhile the air entering 130

by passages H. The oil sprays into said chamber as a hot liquid and mingling with the air entering through passages H, vaporizes and forms therewith the explosive mixture which thenceforward alone supplies the engine.

It is to be especially noted that the oil is merely heated to bring it to a condition identical with gasoline at 60° Fahr., the vaporization of which at that temperature would maintain a water pressure of 6 or 8 ounces, or equal to ordinary coal gas pressure.

The foregoing description presupposes that the engine is cold when the operation begins. If this is not the case, or in other words, if the parts are already hot, as would be the case after a temporary stoppage of the engine, it is not necessary to admit gasoline at all, since the oil may already be at a sufficient temperature to vaporize when admitted into the mixing chamber. It is, therefore, to be especially noted, that the gasoline is used in this apparatus as nothing but a priming. It need not be used at all if the oil is already hot. And, when it is used, a very small quantity—a teaspoonful or two—usually suffices. Hence, it is not necessary in an automobile, for instance, to carry more than perhaps a few ounces of this highly inflammable and dangerous hydrocarbon.

I desire to call particular attention to the way I use the oil. It is not brought to the boiling point, but simply to the very much lower temperature at which it evaporates under the pressure existing in the mixing chamber. And this temperature, which may be but 150° Fahr., requires no higher heating of any part of the contrivance. Furthermore, I do not regulate a flow of oil vapor into the mixing chamber, but a flow of liquid oil which does not become vapor until after it passes the valve K and gets into the chamber I. The great trouble in all previous efforts, within my knowledge, to utilize the heavy hydrocarbon in explosive mixtures has been found in the endeavor to regulate a current of gas flowing into the mixing chamber and produced from hydrocarbon previously vaporized somewhere else. Furthermore, the gas passages become successively highly heated and a deposit or coking takes place in them which stops them up. It is practically impossible properly to regulate that gas flow. It is perfectly possible and easy to regulate a liquid flow, for the amount of liquid escaping past the valve per given time then follows ordinary hydraulic laws, and depends chiefly on the extent of valve opening. From each drop of oil passing the regulating valve K into the mixing chamber I, a precisely definite amount of gas will be evolved. Regulate, therefore, the hot oil passing the valve K, and the amount of

vapor resulting from the oil after it has passed that valve will also be regulated. Hence, it is possible to make explosive mixtures containing the heavy hydrocarbon not only in definite proportions, but in those proportions which insure the best combustion in the engine.

I have practically used in the engine of an automobile, in ordinary employment, kerosene and mixtures of kerosene with fuel oil. In the latter instance, I have successfully utilized a mixture of 50 per cent. kerosene oil at 45° Baumé and 50 per cent. fuel oil at 34° Baumé, and it is entirely practicable by my apparatus and method to burn fuel oil alone and without admixture. Generally, it may be stated that the heat of the oil will be determined by the length given to coil F, and for ordinary kerosene oil this length should be so adjusted as to heat said oil to about 150° Fahr., as already stated. For alcohol, a shorter coil will be used, and for oils heavier than kerosene, a longer one.

The function of the air valve L, at the top of casing B, is automatically to produce an additional air supply when called for by increased engine suction, which also increases the volume of oil spray.

I claim—

1. A carbureter for heavy hydrocarbon, comprising a mixing chamber, a heating chamber surrounding the lower portion of said mixing chamber and provided with an inlet port for the exhaust from an explosion engine and a discharge port, in combination with a float chamber for the hydrocarbon located in the heating chamber and a short external coil arranged within the heating chamber and leading from said float chamber to the lower portion of the mixing chamber, substantially as described.

2. A carbureter for heavy hydrocarbon, comprising a mixing chamber, a heating chamber surrounding the lower portion of said mixing chamber and provided with an inlet port for the exhaust from an explosion engine and a discharge port, in combination with a float chamber for the hydrocarbon located in the heating chamber and a short external coil arranged within the heating chamber and leading from said float chamber to the lower portion of the mixing chamber, together with an air inlet passage adjacent the float chamber and opening to the lower portion of the mixing chamber, substantially as described.

3. A carbureter for heavy hydrocarbon, comprising a mixing chamber, a heating chamber surrounding the lower portion of said mixing chamber and provided with an inlet port for the exhaust from an explosion engine and a discharge port, in combination with a float chamber for the hydrocarbon located in the heating chamber and a short external coil arranged within the heating

- ing chamber and leading from said float chamber to the lower portion of the mixing chamber, together with an air inlet passage adjacent the float chamber and opening to the lower portion of the mixing chamber, and a supplemental air inlet opening to the upper portion of said mixing chamber and valve means for regulating the admission of air therethrough substantially as described.
- 10 4. A carbureter for heavy hydrocarbon, comprising a mixing chamber, a heating chamber surrounding the lower portion of said mixing chamber and provided with an inlet port for the exhaust from an explosion engine and a discharge port, in combination with a float chamber for the hydrocarbon located in the heating chamber and a short external coil arranged within the heating chamber and leading from said float chamber to the lower portion of the mixing chamber, said float chamber having a passage opening to the exterior of the carbureter and serving to maintain atmospheric pressure within said float chamber, substantially as described.
- 15 5. A carbureter for heavy hydrocarbon, comprising a mixing chamber, a heating chamber surrounding the lower portion of said mixing chamber and provided with an inlet port for the exhaust from an explosion engine and a discharge port, in combination with a float chamber for the hydrocarbon located in the heating chamber and a short external coil arranged within the heating chamber and leading from said float chamber to the lower portion of the mixing chamber, said float chamber having a passage opening to the exterior of the carbureter and serving to maintain atmospheric pressure within said float chamber, together with a rod extending through said passage for freeing the float valve, substantially as described.
- 20 6. A carbureter for heavy hydrocarbon, comprising a mixing chamber, a heating chamber surrounding the lower portion of said mixing chamber and provided with an inlet port for the exhaust from an explosion engine and a discharge port, in combination with a float chamber for the hydrocarbon located in the heating chamber and a short external coil arranged within the heating chamber and leading from said float chamber to the lower portion of the mixing chamber, said float chamber having a passage opening to the exterior of the carbureter and serving to maintain atmospheric pressure within said float chamber, substantially as described.
